UNITED STATES PATENT OFFICE.

WILLIAM A. DOREY AND HOWARD L. JENKINS, OF NEWARK, OHIO, ASSIGNEES TO
HOLOPHANE GLASS COMPANY, INC., OF NEW YORK, N. Y., A CORPORATION OF
NEW JERSEY.

LANTERN-PLATE.

1,259,492.

Specification of Letters Patent. Patented Mar. 19, 1918.

Application filed April 19, 1917. Serial No. 163,231.

To all whom it may concern:

Be it known that we, WILLIAM A. DOREY and HOWARD L. JENKINS, both citizens of the United States, residing at Newark, in 5 the county of Licking and State of Ohio, have invented certain new and useful Improvements in Lantern-Plates, of which the following is a specification.

The object of our invention is the manufacture of a glass lantern plate, for use in 10 connection with automobiles, street lamps or any illuminating appliance, where it is desirable to prevent the emission of dazzling rays of light beyond a definite angular limit, and at the same time secure great concentration 15 of light close to the specified angular limit. In a preferred form of our invention, used with automobile lanterns, it is desirable to prevent all dazzling rays of light from 20 striking the eye of passers-by and at the same time to preserve a good illumination of the roadway at considerable distance in front of the car or lamp. We achieve these results by use of a prismatic glass construction in 25 combination with a horizontal diffusing shelf or projection.

Figure 1 is a view of the plate used in a preferred form of our invention, seen from the interior of the lamp.

Fig. 2 is a view from the top of the plate.

Fig. 3 is a vertical cross section of the same, shown in use with an automobile head lamp.

Fig. 4 is a vertical cross section of a further form of our invention shown in connection with an automobile head lamp.

Fig. 5 is a view of the top of the plate shown in Fig. 4.

In Figs. 1, 2 and 3, A is the head light plate having vertical concave flutes J on its outer surface B, and upon its interior surface, the following prismatic construction. On its lower half, prisms C are placed concentric with reference to a point slightly 45 above the center of the plate, and increasing in slope out and down from the general surface of the plate, so that light incident on the same, is bent out and down to the horizontal and below it. Above the horizontal 50 center line of the inner surface of the plate, is placed a section containing two types of prisms. At the center are prisms D, concentric around a point slightly below the center of the plate, decreasing in depth toward the 55 center, whose function is to depress the di-

rect light from the lamp to the horizontal and below it. The reflected light striking the prisms D is thrown toward the axis of the lamp and down at a considerable angle. In the same section of the plate, and grouped 60 around prism D as a center, are radial prisms E, whose function is to bend the direct light striking them down to the horizontal, and out at wide angles sidewise. The reflected rays striking the radial prisms E 65 are bent down to the horizontal, and slightly below it, with very little lateral divergence. The uppermost part of the plate has horizontal prisms F on its inner surface, designed to bend the reflected light striking 70 them down to and below the horizontal. The sloping of prisms F is greatest at the line adjoining section D, and becomes gradually less as the top edge of the section F is approached. Direct light emitted in the direction of prisms F is caught by projection y, 75 and is diffused before striking the upper part of the plate. This projection has a contour at the outer edge, substantially that of a hyperbola, formed by intersecting the 80 cone of direct light striking the plate, with a plane perpendicular to the plate.

The operation of this preferred form of the invention is shown with typical light rays in Fig. 3. The light source H is placed 85 in the focus of a parabolic mirror I of the usual type. a is a light ray proceeding from the center of the light source and striking the reflector at a point b, where it will be reflected horizontally in the direction c. d is 90 the ray from the front of the light source striking the reflector at b and will be reflected above the horizontal in the direction e. f is a light ray proceeding from the extreme back of the light source and striking 95 the reflector at point b; it will be reflected below the horizontal in the direction g; that portion of prismatic construction C which receives the upward reflected ray e, is so designed as to bend the light down so that 100 it will be emitted from the plate in the horizontal direction h. The reflected rays c and g, will be bent down to lower angles and emitted in directions i and j; at a point k on the reflector nearer to the light source 105 than point b, the light ray l proceeding from the extreme front end of the light source will make a greater angle with the ray m from the center of the light source striking the point k than the angle between the rays d 110

and a striking the point b . The ray l will therefore be reflected in the direction n at an angle farther above the horizontal than the reflected ray e , and it will therefore be necessary, in order that ray n be emitted in horizontal direction o that that part of the prismatic construction C receiving the ray n be at a greater angle with the general surface of the plate than that part of the prismatic construction which refracts the ray e . In general the spread of the reflected beam will increase as the distance from the points on the reflector to the light source decreases, and therefore the upward divergence of the extreme reflected rays will increase toward the center of the plate, and it will be necessary to increase the slant of the prismatic construction C toward the center of the plate, in order that these extreme upward reflected rays may be refracted down to the horizontal.

Light rays p proceeding from the extreme front point of the light source, and falling directly on the plate at point q will be refracted downward by prismatic construction D so that it will be emitted in horizontal direction r . Light coming direct from any other portion of the filament and striking the point q will be refracted so as to be emitted below the horizontal, the light ray s proceeding from the center of the light source and striking the reflector at point t and reflected horizontally in direction u will strike the point q and be refracted by the prismatic construction D so that it will be emitted in direction v , considerably below the horizontal.

The radial prisms in the portion of the plate E bend the light rays coming direct from the source down to the horizontal and below it, without affecting their lateral spread to a material degree. Their action on the reflected light is to bend it to small angles below the horizontal and slightly outward. That portion of the cone of direct light emitted between the horizontal plane passing through the axis of the lamp and a plane perpendicular to the cross section and intersecting same in line w , will be bent to the horizontal or below it by the prismatic constructions D and E . That portion of the cone of direct light emitted between the plane w , and the convex surface of the cone of direct light of which y' is a section, will be intercepted by the projection y and be diffused. Thus no light will reach the prisms F direct from the light source. w' is a light ray proceeding from the center of the light source, and striking the reflector I at a point v' , it will be reflected horizontally in direction u' . t' is the ray from the back of the light source striking the reflector at v' and will be reflected above the horizontal in direction s' . r' is a light ray proceeding from the extreme front end of the light

source and striking the reflector at the point v' where it will be reflected below the horizontal in direction q' .

That portion of the prismatic construction F which receives the extreme upward reflected ray s' is so designed as to bend the light down so that it will be emitted from the plate in the horizontal direction n' . The reflected rays u' and q' will be bent down to lower angles and emitted in directions m' and k' . This is typical of the action of all the reflected light falling on the prismatic portion F . It is evident that the slant of the prisms will have to be increased toward the center as in the case of lower prismatic portion C . The projection y will intercept and diffuse a portion of the reflected light, but since the general direction of the reflected light is perpendicular to the plate, and the projection is perpendicular to the plate, this action is reduced to a minimum. In the practical embodiment of this invention it will be found that the irregularities and variations existing in light sources and reflectors which may be treated as a virtual increase in size of the light source. As it is essential to suppress dazzling light above the horizontal, we prefer to use the theoretical design of light sources and reflectors in calculating the prismatic portion C and increase the slopes of prismatic portion F beyond the theoretical needs so as to take care of the variations existing in practice. The outer face of the plate may be left smooth, as shown in Figs. 4 and 5. The function of the flutes is to spread and distribute the light rays in a lateral direction, so as to increase the lateral width of the light beam, or break up shadows, or accomplish both purposes. These flutes may be concave, convex, or concavo convex, and may partly or completely cover the outer face of the plate.

In Fig. 4, the light source H is placed in the focus of a parabolic mirror I of the usual form. The prismatic construction on the interior of the plate, is of the same general form as that shown in Figs. 1 to 3. In place of the one projection, three projections are used to diffuse that portion of the direct light emitted above the horizontal, which is not re-directed by the prismatic constructions D and E . That portion of the cone of direct light emitted between a horizontal plane passing through the axis of the lamp and a plane perpendicular to the cross section and intersecting same in line w will fall upon the prismatic constructions D and E and be refracted to the horizontal and below it. That part of the cone of direct light emitted between the plane w and the similar plane x will fall upon the projection y and be diffused. That part of the cone of direct light emitted between a plane w and the similar plane z' will strike the projection z and be diffused. That portion of

the cone of direct light emitted between the plane z' and the convex surface of the cone of direct light of which y' is the section, will be intercepted by the projection x' and be diffused. The action of the reflected light is as before. In cases where more than one projection are used, the outer edges are hyperbolic in contour, and the back edge of all but the outermost, will be substantially a straight line, parallel to the plate surface. The above modification is preferably used when a single projection would give insufficient clearance for the lamp bulb.

Some of the advantages claimed for my invention are set out as follows. At all points in front of the lantern and at either side all dazzling light rays either from the reflector or direct from the lamp when mounted at the usual height are suppressed above a plane 42 inches from the ground and at the same time a soft glow of moderate intensity is emitted so as to make the location of the lantern easily discernible. A strong driving light is projected at a considerable distance in front of the car and below a plane 42 inches from the ground and this beam is spread sidewise to a moderate degree so that the full width of the road may be discerned and sufficient indication given of crossings, turns and moving objects which may cross the path of the vehicle. Diverging direct light striking the prismatic construction E is concentrated immediately below the horizontal and at wide angles sidewise so as to call immediate attention of the driver to moving objects well to the side of the car and to be cleared by the vehicle.

That portion of the entire reflected beam striking the lower half of the plane is symmetrical with reference to that portion of the beam striking the upper half of the plate. Because of the concentric form of the prismatic construction C, the lower half of the beam is depressed slightly downward and out and owing to the horizontal form of the prismatic construction B, that portion of the reflected beam is slightly depressed in a downward direction. If then there be variations in the combination of the light source, reflector and plate tending to produce light and dark streaks in the beam, the different nature of the action of these two prismatic constructions will tend to obliterate such contrasts and produce a beam of uniform brightness.

We have shown and described the diffusing projections in connection with a prismatic construction of a peculiar form adapted to refract substantially all of the light from the reflector, parallel to or below a horizontal plane and at the same time to refract to or below that limit, all of the direct light which can be so re-directed without undue misdirection and absorption of light. The same principles will apply

with changes in distribution below the limiting plane, if the plan of the prismatic construction in the three sections of the plate be somewhat changed, or if the limiting plane, beyond which the light rays are to be refracted be inclined with reference to a horizontal plane, or be swung around with reference to the axis so as to limit the direction of light to one side of the axis of the plate and reflector. Our invention also aims to cover any refracting and diffusing construction in connection with a diffusing member adapted for the purposes described.

Our invention is especially useful in connection with automobile head-lights, but is useful in connection with street lamps, signal lamps or other illuminating appliances where a strong light combined with an absence of blinding light is desired.

In the claims we have used the term projecting member and this may be a single projecting member or it may be a plurality of projecting members interspersed between the prismatic constructions as shown in the drawing.

Having described our invention, what we claim is:

1. A lantern plate for use in connection with a reflector, the plate having a prismatic construction adapted to refract the direct and reflected light rays in specified directions and a light diffusing projection member, adapted to intercept and diffuse such light rays as cannot be so re-directed by the prisms.

2. A lantern plate for use in connection with a parabolic reflector, the plate having a prismatic construction adapted to refract the direct and reflected light rays in specified directions and a light diffusing projection member, adapted to intercept and diffuse such light rays as cannot be so re-directed by the prisms.

3. A lantern plate for use in connection with a specular parabolic reflector, the plate having a prismatic construction adapted to refract the direct and reflected light rays in specified directions and a light diffusing projection member, adapted to intercept and diffuse such light rays as cannot be so re-directed by the prisms.

4. A lantern plate for use in connection with a specular parabolic reflector, the plate having prisms on its interior surface adapted to refract the direct and reflected light rays in specified directions and a projection member adapted to intercept and diffuse such light rays as cannot be so re-directed by the prisms.

5. A lantern plate for use in connection with a reflector, the plate having a plurality of prismatic constructions adapted to refract the direct and reflected light rays in specified directions with interspersed light diffusion projection members adapted to inter-

cept and diffuse such light rays as cannot be so re-directed by the prisms.

6. A lantern plate for use in connection with a reflector, the plate having a prismatic construction and a light diffusing projection member, the prismatic construction being adapted to refract the direct and reflected light rays in directions parallel to or below a horizontal plane, and the projection member being adapted to intercept and diffuse such light rays as cannot be so re-directed by the prisms.

7. A lantern plate for use in connection with a parabolic reflector, the plate having a prismatic construction and a light diffusing projection member, the prismatic construction being adapted to refract the direct and reflected light rays in directions parallel to or below a horizontal plane, and the projection member being adapted to intercept and diffuse such light rays as cannot be so re-directed by the prisms.

8. A lantern plate for use in connection with a specular parabolic reflector, the plate having a prismatic construction and a light diffusing projection member, the prismatic construction being adapted to refract the direct and reflected light rays in directions parallel to or below a horizontal plane, and the projection member being adapted to intercept and diffuse such light rays as cannot be so re-directed by the prisms.

9. A lantern plate for use in connection with a specular parabolic reflector, the plate having a prismatic construction and an integral light diffusing projection member, the prismatic construction being adapted to refract the direct and reflected light rays in directions parallel to or below a horizontal plane, and the projection member being adapted to intercept and diffuse such light rays as cannot be so re-directed by the prisms.

10. A lantern plate for use in connection with a specular parabolic reflector, the plate having a prismatic construction on one surface and a light diffusing projection member, the prismatic construction being adapted to refract the direct and reflected light rays in directions parallel to or below a horizontal plane, and the projection member being adapted to intercept and diffuse such light rays as cannot be so re-directed by the prisms.

11. A lantern plate for use in connection with a specular parabolic reflector, the plate having prisms on its interior surface, adapted to refract the direct and reflected light rays in directions parallel to or below a horizontal plane, and a projection member adapted to intercept and diffuse such light rays as cannot be so re-directed by the prisms.

12. A lantern plate for use in connection with a specular parabolic reflector, the plate

having a prismatic construction and a light diffusing projection member, the prismatic construction dividing the plate into three transverse divisions, adapted to refract the direct and reflected light rays in directions parallel to or below a horizontal plane, and the projection member being adapted to intercept and diffuse such light rays as cannot be so re-directed by the prisms.

13. A lantern plate for use in connection with a specular parabolic reflector, the plate having a prismatic construction and a light diffusing projection member, the prismatic construction dividing the plate into three horizontal transverse divisions, the uppermost having horizontal prisms, the central having prisms at its center concentric with reference to a point at or slightly below the center of the plate and radial prisms surrounding same and the lower division having prisms concentric with reference to a point at or above the center of the plate, such construction being adapted to refract the direct and reflected light rays in directions parallel to or below a horizontal plane, and the projection member being adapted to intercept and diffuse such light rays as cannot be so re-directed by the prisms.

14. A lantern plate for use in connection with a specular parabolic reflector, the plate having an interior prismatic construction and a light diffusion projection member, the prismatic construction dividing the plate into three horizontal divisions, the uppermost having horizontal prisms, the central having prisms at its center concentric with reference to a point at or slightly below the center of the plate and radial prisms surrounding same, and the lower division having prisms concentric with reference to a point at or above the center of the plate, such construction being adapted to refract the direct and reflected light rays in directions parallel to or below a horizontal plane, and the projection member being adapted to intercept and diffuse such light rays as cannot be so re-directed by the prisms.

15. A lantern plate for use in connection with a specular parabolic reflector, the plate having a prismatic construction on one surface and light distributing construction on the opposite surface, and a light diffusing projection member, the prismatic and light distributing construction being adapted to refract the direct and reflected light rays in directions parallel to or below a horizontal plane, and the projection member being adapted to intercept and diffuse such light rays as cannot be so re-directed by the prisms.

16. A lantern plate for use in connection with a specular parabolic reflector, the plate having on one surface a light distributing construction and on the other surface a plurality of prismatic constructions with inter-

- spersed light diffusing projection members, the prismatic and light distributing constructions being adapted to refract the direct and reflected light rays in directions parallel to or below a horizontal plane, and the projection member being adapted to intercept and diffuse such light rays as cannot be so re-directed by the prisms.
10. 17. A lantern plate for use in connection with a specular parabolic reflector, the plate having a prismatic construction, adapted to refract the direct and reflected light rays in specified directions and a light diffusing projection member, the projection member consisting of a glass shelf member adapted to intercept and diffuse such light rays as cannot be so re-directed by the prisms.
15. 18. A lantern plate for use in connection with a specular parabolic reflector, the plate having a prismatic construction and a light diffusing projection member, the prismatic construction being adapted to refract the direct and reflected light rays in directions parallel to or below a horizontal plane, and the projection member, consisting of a glass shelf, being adapted to intercept and diffuse such light rays as cannot be so re-directed by the prisms.
20. 19. A lantern plate for use in connection with a specular parabolic reflector, the plate having an interior prismatic construction and a light diffusing projection member, the prismatic construction dividing the plate into three transverse divisions, the uppermost having horizontal prisms, the central having prisms at its center concentric with reference to a point at or slightly below the center of the plate and radial prisms surrounding same and the lower division having prisms concentric with reference to a point at or above the center of the plate, such construction being adapted to refract the direct and reflected light rays in directions parallel to or below a horizontal plane, and the projection member, consisting of a shelf, adapted to intercept and diffuse such light rays as cannot be so re-directed by the prisms.
25. 20. A lantern plate for use in connection with a parabolic specular reflector, the plate having an interior prismatic construction and a light diffusing projection member, the prismatic construction dividing the plate into three transverse divisions, the upper-
- most having horizontal prisms, the central having prisms at its center concentric with reference to a point at or slightly below the center of the plate and radial prisms surrounding the same, and the lower division having prisms concentric with reference to a point at or above the center of the plate, such construction being adapted to refract the direct and reflected light rays in directions parallel to or below a horizontal plane, and the projection member, consisting of a glass shelf member of hyperbolic contour situated on the interior of the upper half of the plate and adapted to intercept and diffuse such light rays as cannot be so re-directed by the prisms.
30. 21. A lantern plate for use in connection with a specular parabolic reflector, the plate having a light distributing construction and on its upper inner surface a light diffusing projection member, consisting of a glass shelf member.
35. 22. A lantern plate for use in connection with a specular parabolic reflector, the plate having prismatic construction and on its upper inner surface a light diffusing projection member, consisting of a glass shelf member perpendicular to the plane of the plate.
40. 23. A lantern plate for use in connection with a specular parabolic reflector, the plate having light distributing construction and on its inner surface a light diffusing projection member, consisting of an obscured glass shelf member at right angles to the plane of the plate.
45. 24. A lantern plate for use in connection with a specular reflector, the plate having a light distributing construction and on its inner surface a light diffusing projection member, consisting of an obscured glass shelf member of hyperbolic contour at right angles to the plane of the plate.
50. 25. A lantern plate for use in connection with a reflector, having a prismatic construction adapted to refract the direct and reflected light rays in directions parallel to and to one side of a plane which makes a definite angle with the plate, and a light diffusing projection member, adapted to intercept and diffuse such light rays as cannot be so re-directed by the prisms.
